CODING AND DECODING SYSTEM

Matthew H. Loughridge, Bogota, N. J.; William R. Lockridge, administrator of Matthew H. Loughridge, deceased

Application March 31, 1941, Serial No. 386,169

9 Claims. (Cl. 246—2)

1

This invention relates to coding and de-coding systems such as may be used in accounting work and statistical records, it is however of general application, and also is shown in one form in connection with controlling traffic on a railroad.

An object of the invention is to provide a code selector system operated inductively by scanners, and also to provide a system of this kind operating between a moving vehicle and trackway devices for selectively registering the movement of the vehicle, or for directing its course on the track.

Other objects are to provide a code selective system located partly on a vehicle and partly on the trackway with means for operating apparatus on the trackway according to a code, and other for operating an apparatus on the vehicle according to a predetermined code.

Another object of the invention is to provide a code selective system for operating track switches by an approaching vehicle with means for changing the code for each vehicle.

Another object of the invention is to provide a code selective system with a change-over control for operating according to one code and then changing over to operate according to another code.

These and other objects of the invention will be more particularly understood from the following specifications and the accompanying drawings, in which:

Fig. 1 is a circuit diagram of one portion of the code selector system which may be located on a vehicle or moving object;

Fig. 2 is a circuit diagram of the scanners for operating the system shown in Fig. 1;

Fig. 3 is a circuit diagram of a portion of a second code selector system which is operated, through a change over mechanism, by the system shown in Fig. 1;

Fig. 4 is a circuit diagram of a de-coding system using rotary de-coding members for each element of the code;

Fig. 5 is an elevation of the de-coding discs shown in Fig. 4;

Fig. 6 is a graphic representation of the code system used in Figs. 1 to 4;

Fig. 7 shows an application of the system in Figs. 1 and 2 for the selective operation of a turn-out switch on a railway track;

Fig. 8 shows an application of the system in Figs. 1 and 3 for describing a train on a railway track, and

Fig. 9 shows an alternative arrangement for

2

operating the circuits between the trackway and the vehicle by the use of resonant circuits.

Fig. 10 is a top plan view of a three-position relay switch used in Fig. 1;

Fig. 11 is a side view, in elevation, of a portion of Fig. 10;

Fig. 12 is an end view from the top end of Fig. 10, partly sectioned, showing the arrangement of the contact fingers;

Fig. 13 is an end view from the lower end of Fig. 10, showing the operating magnets and the toggle mechanism controlling the circuits, and

Fig. 14 is a front view of the toggle member used in Fig. 13.

15 This invention is based upon the application of a coded system in a variety of forms, which coded system is described in the following co-pending applications: 205,186, April 30, 1938, Code selective systems, now Patent No. 2,266,779, December 23, 1941; 248,894, Dec. 31, 1938, Coding machine, now Patent No. 2,269,293, January 6, 1942; 282,833, July 4, 1939, Inductive selector, now Patent No. 2,323,822, July 6, 1943; 315,300, Jan. 24, 1940, Pneumatic selective system, now

20 Patent No. 2,378,489, June 19, 1945; 344,493, July 9, 1940, Code selective apparatus, now Patent No. 2,320,150, May 25, 1943. A variety of decoding systems, part of which are shown in this application, also are included in application,

25 Serial No. 417,969, filed November 5, 1941, now Patent No. 2,387,850, October 30, 1945.

The apparatus shown in connection with Figs. 1 to 9 inclusive relates to railway systems and the control of traffic thereon; it should be understood, however, that the principles of the invention are of general application and their association with railway systems is shown as a matter of convenience.

30 The code selective system is applied by apparatus on the vehicle which is operated by scanners on the trackway, selectively to set up conditions for operating turn-out switches on the track according to a prearranged code. The vehicle apparatus is controlled by a code selector switch so that the code may be changed to operate switches on different tracks. The impulses between the vehicle apparatus and the trackway scanners are transmitted inductively and simultaneously.

35 The system also provides for describing the train according to a code and for this purpose a second code system is provided on the trackway to be operated by scanners from the vehicle as it passes over the trackway devices. This arrangement is also operated inductively and simultaneously.

40 The system also provides for describing the train according to a code and for this purpose a second code system is provided on the trackway to be operated by scanners from the vehicle as it passes over the trackway devices. This arrangement is also operated inductively and simultaneously.

45 The system also provides for describing the train according to a code and for this purpose a second code system is provided on the trackway to be operated by scanners from the vehicle as it passes over the trackway devices. This arrangement is also operated inductively and simultaneously.

50 The system also provides for describing the train according to a code and for this purpose a second code system is provided on the trackway to be operated by scanners from the vehicle as it passes over the trackway devices. This arrangement is also operated inductively and simultaneously.

55 The system also provides for describing the train according to a code and for this purpose a second code system is provided on the trackway to be operated by scanners from the vehicle as it passes over the trackway devices. This arrangement is also operated inductively and simultaneously.

tively, and by a change-over switch on the vehicle certain of the inductors which were used for the first code selector are made available as scanners to operate the second code selector. The change-over mechanism is operated by trackway devices to establish the second code, and when the train is to be described by more than one code, a three-position relay switch is used on the vehicle to change over the system to describe the train first under one code and, secondly, under the second code at the next track location.

The scanners that operate the code selector system on the vehicle for operating the switch are de-coded according to the designation of the switch so that when the scanners and the switch designation synchronize, the switch is operated but at other times it is not operated. The decoding for describing the vehicle, on the other hand, must be translated in a legible form and is usually recorded by the de-coding mechanism. In the present application the code is made up of three characters, each of which may include the numbers from 0 to 9 and the code may be de-coded into any combination of these numbers.

In the direct de-coding system a de-coding relay is provided for each position in the base of the code and when any three of these relays are energized a code is established.

The impulses for operating the system between the scanners and the coding apparatus may be operated by contacting members establishing an electric circuit for the operation of the coding relays; it may be operated by electro-magnetic induction, or it may be operated by photo-electric cells controlled by a light beam. The system is shown operated by electro-magnetic induction in which a movable inductor moves over a relatively fixed inductor to give the impulse or the transmitting inductor may be energized by alternating current. The same inductor may be provided with two or more coils, each included in a resonant circuit and arranged to operate a corresponding resonant circuit which makes each inductor equivalent to separate inductors with the same number of coils. A single impulse can be made to operate the relay, or a prolonged impulse may be used; it is essential, however, in a code of this type in which all the selected relays function at the same time that the impulses be made simultaneously, that is so arranged that the selected code relays will all be energized at the same time.

The three position relay has a neutral position and a coil for moving it in one direction from the neutral position and a second coil for moving it in the opposite direction from the neutral position. The relay includes a toggle mechanism which, when the relay is operated in one direction, is shifted to the opposite position to establish the circuit of the opposite coil for the next operation. This mechanism works both ways and insures that the relay each time it is energized alternately operates in opposite directions.

The code selector circuit

In the drawings, the reference characters 0 to 9 indicate the apparatus of each of the code circuits which is repeated for each circuit and will be understood by the description of the circuit of one code character. These numbers are also used for designating the particular codes, as a matter of convenience.

In Fig. 1, showing the apparatus which would be mounted on the vehicle in this example, 21 is

an inductor provided with a coil 22, connected by circuit 23, through contact finger 24, with the full wave rectifier 25. One side of the output of this rectifier connects to the common wire 26 for all the inductors, and the other side, through wire 27, and a contact 28, on the bail 29 of the code selector switch connects to the appropriate disc 30 of that switch. The circuit continues by conductor 31 to the code relay 32 the other side of which is connected to the common wire 26. This circuit is repeated on each set of inductors from 0 to 9 to operate the corresponding set of code relays from 0 to 9 through the code selector switch. In each position the bail 29 establishes a circuit from its contacts 28 to three only of the discs 30 of this code selector switch, the drawings indicating that the circuit is established to code discs 1, 3 and 5 which thus establishes the code used for the illustration. When the bail 29 is moved a new set of circuits is established between its contacts 28 and the contacts of the other discs 30, thus establishing a new code.

The code relays 0 to 7 are provided with contact fingers 33, relays 1 to 8 are provided with contact fingers 34, relays 2 to 9 with contact fingers 35, and relays 3 to 9 with contact fingers 36. These fingers control a row of parallel circuits through their back contacts 37, 38, 39 and 40, respectively, which repeat from relay to relay as shown. The fingers also control a set of circuits through their front contacts by conductors 41, 42 and 43 which transfers the circuit at each energized relay from one parallel row to the next parallel row. The circuit starts at relay 0 in the direction of the arrow and ends at contacts 35, 36 of relay 9, which latter connect to conductor 44 and the back contact 45 of relay 46 to conductor 47 which energizes relay 48. The return circuit is connected from the arrow point at relay 48 to the arrow at contact 33 of relay 32 of code relay 0. The repeating circuit controlled by the code relays is so arranged that any three of the code relays in the energized position and the remaining relays in the deenergized position will energize relay 48. Any other combination of code relays will interrupt instead of completing the circuit of relay 48.

When relay 48 is energized a circuit is established from transformer 51, through front contact 49 of relay 48 and conductor 52 to coil 53 of another inductor, indicated at X, and its return circuit on conductor 54. When relay 48 is energized a circuit is also established through front contact 50 to conductor 55 and magnet 56 on bail 29 of the code selector switch. Magnet 56 operates a spring controlled ratchet, not shown in the drawings, which, when magnet 56 is released, moves the bail 29 forward one step to establish a new code.

The scanning apparatus in Fig. 2, mounted on the trackway in this example comprises a plurality of inductors 57 each with a coil 58, connected by circuit 59 with the transformer 60. Three of these inductors are shown in multiple circuit to register with inductors 1, 3 and 5 of the apparatus of Fig. 1, which transmit operating impulses to circuits connected with inductors 1, 3 and 5, when the bail is in the position shown, to correspondingly energize the code relays 1, 3 and 5 and thereby energize relay 48. This also energizes the impulse inductor X by the circuit already described which in turn transmits impulses to track inductor Y. The coil 61 of inductor Y is connected by circuit 62 with the rectifier 63 and by circuit 64 to the trans-

lating device 65 that is used to register the code in any manner desired. It will be noted that when bail 29 changes to a new code position the track inductors 57 next encountered must be located to register with the train inductors 21 that bail 29 brings into circuit in the new position, otherwise the system will not synchronize. That is to say the track inductors 57 are located to register with the desired vehicle inductors 21 of code positions 0 to 9; and since the system illustrated uses a code base of three, the three track inductors 57 can be arranged in any of one hundred twenty different combinations with the ten vehicle inductors.

As explained, each time a set of code impulses are transmitted through the code selector switch to the code relays the magnet ratchet mechanism 56 steps the bail to the next selected code position, thus conditioning the circuits to function when the next set of track inductors is encountered, or the set corresponding to that setting of the code selector switch.

When the train carried inductors 21 are to be used as scanners, the magnet 79 with its associated mechanism may be added to the train carried mechanism, and the decoding relays of Fig. 3 located along the trackway. Magnet 79 functions through armature 76 on contact bar 75, which carries the stud members 77 and 78. The stud members 77 are on the lower side of bar 75 and when magnet 79 is energized the bar 75 is moved downwardly so that these studs engage the contacts 24 at each location by moving the bar 75 downwards, to open the circuit to the respective rectifiers 25 and close the circuits to the conductor 85, through the respective contacts 86. The stud members 78 on the upper side of bar 75 are in an inactive position and do not influence the contacts 24, but all are manually adjustable to active or inactive positions to establish any code desired. When magnet 79 is energized the circuit to the coil 22 of inductor 1, inductor 3 and inductor 5 are connected to transformer 83 through conductor 85, the return circuit being established by the common conductor 45. This places the inductors 1, 3 and 5 in condition to transmit impulses to registering inductors, such as 97 illustrated in Fig. 3.

Transformer 89 (Fig. 3) through circuit 90 and condenser 91 energizes coil 92 of inductor Y'. This transmits impulses to inductor X, energizing its coil 53, and through circuit 54, primary of transformer 94, conductor 93, back contact 49 of relay 48 and return circuit 52, transformer 94 energizes relay 46, through circuit 95 and condenser 96 which is resonant to condenser 91. Relay 46 energized disconnects relay 48 at 45 and through contact finger 81 and conductor 80 energizes the change-over magnet, or relay, 79. A circuit is also established through contact finger 82 of relay 46 to energize transformer 83, which energizes the inductors brought into circuit by the magnet 79.

A second row of inductors are indicated in Fig. 3, which may be located along the trackway, and which register with the corresponding inductors in Fig. 1. Each of these includes the inductor 97 with the coil 98 which, through rectifier 99 and circuit 100, energizes the de-coding relays 101, respectively. In the circuit as shown in Fig. 3 inductors 1, 3 and 5 are in circuit when relay 79 is energized and de-coding relays 1, 3 and 5 are energized while the remaining relays are de-energized.

In this arrangement it will be noted that the 75

scanning inductors in Fig. 2 operate the coding relays of Fig. 1 through the code selector switch by means of which any predetermined code may be established. When the code is established impulses are transmitted between inductors X and Y which operate the translating device 65.

The de-coding system in Fig. 3 may be brought into use, when the scanning system in Fig. 2 is not required. In order to effect this change-over 10 the energized inductor Y' transmits impulses to inductor X which energizes the change-over relay 79, thereby changing the inductors 21 to scanning inductors to operate the de-coding relays 101 according to the selected circuits determined 15 by the studs 77 on the bar 75.

In applying this system, three sets of impulses are simultaneously brought into use to establish the code desired; there is no interval needed between these sets of impulses and therefore the 20 apparatus is always ready for operation and its operation is relatively speedy. It should be understood that certain timed relation is necessary to secure the proper sequence of operation, for instance, the change-over relay 79 should be operated by the time the inductors 21 and 97 come into register. For this purpose, if the inductors 21 are moving relative to 97, the inductor Y' may be located to register with inductor X in advance of the other inductors so as to energize relay 46 and magnet 79 to effect a change over at the proper time. Magnet 79 and relay 46 are indicated as of the slow releasing type so as to maintain the operating conditions established by inductor Y' after the inductor X has passed out of register with Y'. The particular method of securing the time sequence in the operation of the system will depend upon the purpose to which it is applied. For certain purposes an electric or pneumatic slow release may be used for 46 and 79, and in other cases, where the time factor may be prolonged, the usual plan is to provide a stick relay control which will maintain the established conditions until the function is completed.

De-coding system

A system for de-coding the elements of the code separately is shown in Figs. 4 and 5 and uses the electric motorstat shown in my said application Serial No. 282,833, now Patent No. 2,323,822, issued July 6, 1943. The de-coding relays 101 are provided with contact fingers 1102, 1103 and 1104 which control a circuit from relay to relay through the back contact of the first finger and conductor 131, also a second circuit controlled by the back contact of the second contact finger and conductor 132 from relay to relay and a third circuit through the back contact of the third contact finger through conductor 133 from relay to relay. A circuit is also controlled from a front contact of the first finger by conductor 134 to the second finger of the next relay and another circuit is controlled by conductor 135 from the front contact of the second contact finger to the third contact finger of the adjoining relay.

Three motorstats, A, B and C are operated by the de-coding relays and are provided with numerals or other marks so that the selective position in which the rotor is stopped corresponds with the numeral of the code which is represented by the controlling relay. The stator is provided with poles numbered from 0 to 9 and with a rotor which is non-magnetic and is driven by means not shown in the drawings. The rotor is provided with a magnetic iron bar which reg-

isters with each of the poles of the stator as it rotates and if the coil of the pole is energized by direct current it is magnetically stopped opposite the energized pole.

When relay 101 of the decoding relays is energized a circuit is established through 1102, conductor 136 to coil 0 of motorstat A and return by the common conductor 146. When the next decoding relay 1 is energized and the first decoding relay 0 is deenergized, a circuit is established in conductor 137 to coil 1; when relay 2 is energized and relays 0 and 1 are deenergized a circuit is established by conductor 138 to coil 2, and when relay 3 is energized and relays 0, 1 and 2 are deenergized a circuit is established through conductor 139 to coil 3. In the same way, the front contact finger of relays 4, 5, 6, 7, 8 and 9 energize the corresponding coils of the motorstat A when each relay is energized and the preceding relays are deenergized.

When relays 0 and 1 are energized a circuit is established on conductor 137 to coil 1 of motorstat B; when relay 0 is deenergized and relays 1 and 2 are energized a circuit is established on conductor 138 to coil 2 of B. In the same way each of the coils of motorstat B are energized progressively by the code relays when any two of these relays are energized and the preceding relays are deenergized. A circuit is established to conductor 138 for coil 2 of motorstat C when relays 2, 1 and 0 are energized; a circuit is established to coil 3 when relays 3, 2 and 1 are energized and relay 0 is deenergized. In the same way the remaining coils of motorstat C are energized progressively by the succeeding code relays when any three of the relays are energized and the remaining preceding relays are deenergized.

It will be noted that the first relay energized from the entering side of the circuit positions the motorstat A according to the location of this relay in the group, the second relay energized from the entering side of the circuit positions the motorstat B according to the location of this relay in the group and the third relay energized positions the motorstat C according to the position of this relay in the group. The operation of B is subject to the control of A and the operation of C is subject to the control of A and B. Other known systems of decoding may be used instead of that shown in this figure.

Fig. 5 shows one arrangement of the motorstats A, B and C mounted on a stand 1340 and provided with a platen 1350 which may be operated to register the position of each of these discs after a code has been established.

Graphic representation of the code

The code to which this system is applied is graphically represented in Fig. 6 in which the base of the code is represented by 149 and by the horizontal lines from 0 to 9. The characters of the code are indicated by the circles on the cross lines and by the numbers 150 in the horizontal row. For each code three characters are used and they are positioned on the base in such a way that at least the position of one of the characters for a particular code differs from all other codes. Opposite line 012 the three characters on the base are indicated on line 012 which may be regarded as the starting position and represents the first code designated by 012. For the next code the character on line 2 of the base is changed to line 3, making the code 013; for the next code the character on line 3 of the base is

changed to line 4 making the code 014, and so on for each of the remaining characters until code 019 is reached; the position of the characters in the code base can easily be read on the cross lines. The code 019 exhausted this group and the next code is set up by moving character 1 on the base to the position of character 2 and moving character 2 to the position of character 3; this sets up the code 023; the next code is established by changing character 3 on the base to position 4, setting up code 024 and this condition is repeated until code 029 is established. The next code 034 is established by a character in position 0, the next character in position 3 and the next character in position 4 corresponding with 034; the next code 035 is established by changing the position of character 4 to position 5 and so on until code 039 is established. The designation of the code in each case is obtained from the position of the code characters on the base as indicated at 149.

When the positions of the second and third characters on the base are exhausted the first character is moved from position 0 to position 1 and the second and third characters are moved accordingly. This condition is indicated at the right in Fig. 6 in which the code 123 is established by the characters on the corresponding base lines.

In order to prevent the same characters from repeating in the code, it is usual to apply the characters in ascending order, for instance, when code 123 is used then code 132, which has the same characters, should not be used. This idea is carried out in the operation of the motorstat in Fig. 4 in which the circuits for operating disc A for all positions are provided, while the circuit for operating disc B to position 0 is omitted and the circuits for operating disc C to position 0 and 1 are omitted.

For a code of this type, having three changeable characters, used in ascending order, the capacity is the product of the three highest numbers of the base, divided by the product of the number of changeable characters. This may be applied as follows: Let X, Y, Z represent the three highest numbers in the base of the code, then:

$$N = \frac{X \times Y \times Z}{1 \times 2 \times 3}$$

By this formula a code having three changeable characters on a base of 10 has a capacity of 120 and the system having three changeable characters on a base of 12 has a capacity of 220. The code can readily be expanded as found necessary and the principles of the invention can be expanded to code and decode for any increase desired. The relays by which the system is applied operate a code having a common base and operate on the group plan. The same group of relays always produce the same results. They are usually arranged in ascending order so that the same relays do not repeat for different codes.

Application to control of railway traffic

The selective operation secured by this coding system may be used for controlling railway traffic as indicated in Figs. 7, 8 and 9 and in Figs. 1, 2 and 3. The apparatus in Fig. 1 may be carried on a moving train while the apparatus in Figs. 2 and 3 may be located on the trackway so that the train carried apparatus is movable relative to the trackway apparatus. The application in Fig. 7 is for the selective operation of track switches in

which 18 and 19 represent the rails of the track and 136 is the code number of the first switch. The trackway inductors 57 are placed in locations 1, 3 and 6 as indicated by the dotted line to operate the code selector system in Fig. 1, thereby energizing inductor Y and operating the switch apparatus which, in this instance, corresponds to the translating device 65 of Figure 1.

It will be understood that the track inductors 57 have previously been located in the predetermined code positions 0 to 9 for each switch. Also the contacts on the discs 30 of the code selector switch have been pre-set in the particular order desired and to correspond with the codes of the switches in the order to be encountered so that the proper circuits will be made through contacts 28 of bail 29 of the code selector switch to the code relays 32, all as has heretofore been described.

In Fig. 7 the switch to the right is operated by a code which is manually established and which may be changed at will so that the operator can switch any approaching car to the turn-out switch whose code he already knows. The inductors 57 connect by conductors 59 to a row of parallel bars over which the crossbar 151 is placed and may be plugged into the circuit of any of the conductors 59 by the plugs 160, 161 and 162; the bars selected correspond with the code desired. A stick relay 155 has a pick-up circuit 156, closed by the push button 157 to energize the relay and close a holding circuit through contact finger 158, conductor 159 and back contact finger 72 of relay 68. This circuit holds relay 155 energized until the train passes over the switch. Transformer 60, through contact finger 152, when relay 155 is energized, energizes bar 151 and thereby energizes the selected inductors 57. If the control by the stick relay 155 is not required, a shunt circuit around this relay is provided by switch 154 and conductor 153.

When inductor Y is energized relay 65 is energized through conductor 64 and through front contact 69, and conductor 70 energizes the switch operating mechanism 71 for reversing the switch. After the train passes over the switch it passes over the inductor Z indicated at 66 which is momentarily energized by train carried inductor X and energizes conductor 67 and relay 68. This closes the front contact 72 to conductor 73 which energizes the switch mechanism 71 to operate the switch from the reverse to the normal position. Energizing relay 68 interrupts the circuit of the stick relay 155 and restores normal conditions until the push button 157 is again operated. A developed circuit for controlling the switch is shown in U. S. Patent 1,881,317, June 14, 1921, to Loughridge.

The arrangement in Fig. 8 shows two sets of inductors placed on the trackway for receiving code signals from the train or vehicle. One set of these inductors is placed at one side of the station P and another corresponding set is placed at the opposite side of the station. When one set of code signals only are to be transmitted to the trackway for describing the train, only one set of trackway inductors are required with a change-over arrangement by relay 79 as indicated in Fig. 1. If the train is to be described by two sets of codes, one representing the point of origin, and the other representing the destination, then the two sets of trackway inductors are required with a three-position change-over relay as shown in Figs. 10 and 11.

Fig. 9 indicates an arrangement of resonant circuits on the inductors in which two coils, 58a

and 58b, may be placed on the same inductor, each of which are connected with condensers 163. The same arrangement is applied on the vehicle for coils 22a and 22b which include the condensers 164 resonant to 163. The resonant circuits obtain the results with fewer inductors.

Three-position relay switch

The three-position relay switch shown in Figs. 10-14 may be substituted for the change-over magnet 79 and operates from a neutral position to the right and from the neutral position to the left, the right and left positions setting up different conditions in the circuits controlled by the device. In the operation shown a spring restores the device to the neutral position when the operating magnets are deenergized. When the magnet to the right is energized the switch is moved from the neutral position to the right and when the magnet at the left is energized the switch is moved from the neutral position to the left. In the present application the operating magnets are so controlled by the mechanism that the switch moves from the neutral position to the right, then back to the neutral position, then from the neutral position to the left and back to the neutral position and then to the right again, alternately from the neutral position to the right and to the left for application to the trackway arrangement shown in Fig. 8.

This mechanism comprises a stand 206 supporting a shaft 205 upon which sockets 203 and 204 are mounted and these sockets carry the insulated bodies 201 and 202 of the switch mechanism. Arm 207 is mounted on shaft 205 and is provided with a spring 208, Fig. 12, connected to the frame or stand 206, which applies a bias to the shaft 205 to bring the bodies 201 and 202 to the neutral position.

40 The body 201 is provided with a row of ten keys, 210, which can be depressed against the spring 212 so that the insulated lower end 213 of stud 77 is in position to engage the contact finger 24, mounted on the base 209. The body 201 also 45 is provided with a row of ten plungers 218, each of which has a stem body 215 sliding in a slot 214 in the corresponding key 210. This stem body is provided with an inclined surface 216 which engages the slot 214 in the corresponding key 210. 50 By this arrangement each plunger that is pressed inwardly in the row 218 depresses the corresponding key in row 210 and holds these keys depressed so that the selected studs 77 are positioned to set up the circuits desired when the switch is operated to the position to bring this row of contacts into use. A plate 219 is mounted on the stem of the plungers 218 and through which the plungers freely move. This plate is provided with a handle 220, which when withdrawn, withdraws the plungers in the row 218 to the released position, thereby restoring the keys in row 210 and placing the mechanism in condition for a new set of plungers to be operated. The insulated body 202 is provided with a corresponding set of keys 211 which are operated in a similar manner by the row of plungers 218. The end of the plunger stem 215 is provided with a hook 217 which secures a latching engagement between the plunger 215 and the key 210 so that the plunger cannot be moved out of place accidentally.

60 The shaft 205 is operated to the right and to the left by the operating magnets 79, 79', mounted by their back strap 227 on the frame 206, Fig. 13. Magnet 79' is of the solenoid type and operates 65 a plunger 230 connected by the link 229 with the

arm 228, mounted on shaft 205. Magnet 79 operates plunger 232 connected by link 231 with the opposite end of arm 228. By this construction the arm 228 is tilted to the position indicated by the dotted lines which moves the bodies 201 and 202 clockwise when magnet 79' is energized, and counter-clockwise when magnet 79 is energized.

A control member 235 is mounted to slide horizontally on the disc 237, secured to frame 206, by the screws 236 engaging the slots in 235 as indicated. A toggle mechanism 245, having a plunger controlled by spring 244 engages a notch 243 on the sliding member 235 so that when this member passes beyond the center the toggle completes its movement in either direction.

The sliding member 235 is provided with an inclined finger 238 pivoted at 239 and normally resting on the stop 241. This member is free to move away from the stop like a ratchet and is engaged by the pin 234 on the arm 228 as this arm is moved upwards by the magnet 79 until the pin assumes the position indicated at 234'. When magnet 79 is deenergized the mechanism is restored to the neutral position by spring 208, this brings the pin 234 into engagement with the inclined finger 238 and moves the sliding member 235 to the left, which movement is completed by the toggle 245. A corresponding construction is provided at the opposite end of the sliding member 235 in which pin 233 in the arm 228 engages the finger 242 when the pin returns from the position indicated at 233' to the normal position, thereby moving the sliding member 235 back to the position shown. Member 235 carries the insulated contact finger 721 controlling the circuit of magnets 79 and 79'. The circuit is established from the control wire 80 through finger 721 to contact 722 on disc 237, wire 723 to magnet 79 and return on wire 724. This energizes magnet 79 when wire 80 is energized. After magnet 79 has operated and the mechanism is restored to the neutral position, the contact finger 721 is disconnected from contact 722 and connected to contact 725 and through wire 726, magnet 79' is energized for the next operation. After this operation is completed and the mechanism restored to the neutral position, contact finger 721 is again connected with 722 and disconnected from contact 725 to repeat the cycle of operation.

The circuit in Fig. 1 shows an arrangement in which magnet 79 controls one set of contacts 24 only. When two sets of contacts are controlled, as in the application of the three-position relay switch, the circuit controlled thereby is modified as indicated in Fig. 12. In this circuit it is necessary that the operation to one position will disconnect relays 32 and connect the inductors 21 with the transformer 83; it is also necessary that the same results be obtained when the switch is operated to the opposite position.

For this purpose the circuit on wire 23 is continued through contact 221 (Fig. 12) on the base 209, contact finger 24, conductor 24b, contact 221a at the opposite side, contact finger 24a and conductor 24c to coil 22 of inductor 21, thereby connecting the inductor in series with relay 32 through the rectifier 25. This is the normal condition. When contact 24 is depressed by the switch mechanism, a circuit is established from transformer 83, through 85, contact 222, contact finger 24, conductor 24b, contact 221a, contact finger 24a, conductor 24c to coil 22 of inductor 21 and return on conductor 81. This disconnects the rectifier 25 and relay 32 and places inductor 21 in condition to operate as a scanner. When

contact finger 24a is depressed, the circuit to conductor 24b is interrupted, thereby disconnecting 25 and 32 and conductor 24c is connected through contact 222a to 85 and transformer 83 to energize the inductor 21 for scanning purposes.

When applied to a railway system as in Fig. 8, the three-position relay switch adjusts the system to operate first from a code set up on the body 201 of the switch and at the next location to operate the system according to a code set up on body 202. This conditions the system for a corresponding operation at the next location.

This system admits of extensive expansion and, if necessary, for this purpose the base of the code can be increased so that a large number of functions may be remotely controlled from a central point and according to a predetermined selection. The apparatus necessary for carrying out this system is commercial stock and may be readily assembled from existing sources.

Having thus described my invention, I claim:

1. A railway system comprising a track with a turnout switch thereon, means for operating said switch, a vehicle on said track, a code selector on said vehicle, means on the track for operating said code selector, means connecting said code selector with said switch operating means, manually controlled means on the track for adjusting said connecting means to operate the switch by any one of a group of codes and means for cancelling said manually controlled means after the vehicle passes over the switch.

2. A coding system for describing a train on a railway track, comprising a plurality of inductors on the train spaced and energized according to the code desired, a row of receiving inductors on the track arranged each to receive impulses simultaneously from said inductors on the vehicle, a circuit connected with each of said receiving inductors, a relay in each circuit, each relay in the circuit registering with an energized inductor being energized thereby and the remaining relays being deenergized, and means for registering the code represented by said energized relays in the energized position together with the remaining relays in the deenergized position.

3. A coding system for describing a train on a railway track, comprising a row of spaced inductors on the train, a row of registering receivers on the trackway, means for selectively energizing a predetermined number of said inductors, a relay controlled by each receiver, the relay for each receiver registering with an energized inductor being simultaneously energized thereby and the remaining relays being deenergized, and means for registering the code represented by said energized relays in the energized position together with the remaining relays in the deenergized position.

4. A system for transmitting a code from a vehicle to the trackway, comprising a row of inductors on the vehicle, means for selectively energizing said inductors, a row of inductive receivers on the trackway registering with said vehicle inductors, a translating device operated by each of said receivers and registering the code transmitted by said vehicle inductors, and means on the trackway controlling said vehicle energizing means as the inductors and receivers come into register.

5. A code selective system for operating railway switches from cars on the track, comprising scanning devices on the track adjacent the switch and arranged with a character peculiar to each

switch on the same track, a car having a group of relays normally deenergized, means on the car for receiving an impulse from each scanning device for operating a particular relay of the group corresponding with the scanning device, adjustable apparatus on the car controlling the circuit of each relay of the group so that a predetermined number of said relays will be operated by a predetermined arrangement of said scanning devices, a translating device having a circuit established by said predetermined relays in the energized position and by all the other relays in the deenergized position, and means controlling said switch by said translating device.

6. A code selective system for operating railway apparatus from cars on the track, comprising a track with scanning devices located at intervals thereon and each arranged with a characteristic peculiar to a particular code, a car having a group of relays normally deenergized, means on the car for inductively receiving an impulse from each scanning device for operating together particular relays of the group according to the code represented by the scanning devices, a translating device having a controlling circuit established by said particular relays in the energized position and by all the other relays in the deenergized position, and means controlling the railway apparatus and controlled by said translating device.

7. A railway system comprising a track with a turnout switch thereon, means for operating said switch, a vehicle on said track, a code selector on the vehicle, a plurality of members on the track

transmitting impulses to the vehicle to operate the code selector, manual means for controlling the operation of said transmitting members according to the code desired, and means on the track cooperating with the code selector controlling the switch operating means.

8. A coding system for controlling traffic on a railway track comprising a plurality of sets of members spaced on the track upon each of which a code, set up by impulses, may be registered by a group of said members, electrically controlled means on the vehicle registering with the trackway members for operating said members, a vehicle on said track, a device on the vehicle controlling said electrically controlled means, means for adjusting said device to control said trackway members according to the desired code, and means on the trackway for operating said device.

9. A coding system for controlling traffic on a railway track comprising a plurality of sets of members spaced on the track upon each of which a code, set up by impulses, may be registered by a group of said members, a vehicle on the track, electrically controlled means on the vehicle registering with the trackway members for operating said members, a device on the vehicle controlling said electrically controlled means, means on the trackway for operating said device, and manually adjusted means controlling said sets of trackway members to change the code to which said members respond.

MATTHEW H. LOUGHRISE.
